(57) **CLAIM**

The ornamental design for a camping lamp, as shown and described.

DESCRIPTION

FIG. 1 is a front perspective view of a camping lamp showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a rear perspective view thereof; and,

FIG. 8 is a perspective view thereof, showing the camping lamp in an alternative, open configuration of use.

The broken lines in the drawings depict portions of the camping lamp that form no part of the claimed design.
